UNITED STATES PATENT OFFICE.

DENNIS J. O'BRIEN, OF JEROME, ARIZONA, ASSIGNOR OF ONE-FOURTH TO JOHN P. HARRINGTON, ONE-FOURTH TO THOMAS J. NAGLE, AND ONE-FOURTH TO JOHN L. MURRAY, ALL OF JEROME, ARIZONA.

STAY-BOLT.

1,126,895.

Specification of Letters Patent. Patented Feb. 16, 1915.

Application filed October 6, 1914. Serial No. 865,230.

To all whom it may concern:

Be it known that I, DENNIS J. O'BRIEN, a citizen of the United States, and a resident of Jerome, in the county of Yavapai and State of Arizona, have invented a new and Improved Stay-Bolt, of which the following is a full, clear, and exact description.

My invention relates to stay bolts, and has reference more particularly to the flexible type of stay bolts associated with a partition in the boiler for perfecting the circulation of the fluid to be heated.

An object of the invention is to provide a stay bolt and partition of simple, strong and durable construction, which bolt has means for readily indicating any injury thereto, and which will insure at all times a uniform tensile strength.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a section through a fragment of a boiler provided with an embodiment of my invention; and Fig. 2 is an end view of the tension-control bolt in the direction of the arrow 2, in Fig. 1.

Referring to the drawings, 3 represents the fire sheet of the boiler, and 4, the outside plate or sheet of the boiler. Positioned between the sheets 3 and 4 is a partition 5, formed of a metal sheet, not extending entirely to the bottom of the boiler, and which is secured to the fire sheet 3 by screws 6 screwed into the fire sheet and the said partition 5. The partition is also secured to the outer sheet 4 by bolts 7, the heads 8 of the bolts being rounded where they contact with the sheet. The opening in the partition engaged by the bolts 7 gives the partition freedom of movement laterally to the bolts, said bolts 7 being only screwed into the outer sheets 4. The ends of the bolts 7 which project exteriorly of the said outer sheet 4 are reduced and shaped angularly, as shown at 9, to be easily engaged by a suitable wrench, and by screwing said bolts 7 the tension of the screws 6 is controlled.

The bolt 7 is provided with a central bore 55 10, which forms the tell-tale hole of said bolt through which a leak will be established when the bolt is ruptured.

It will be noted that the partition plate 5 is suspended between the fire-box sheet 3 60 and the outer sheet 4 of the boiler. The screws 6 connecting the fire-box sheet to the partition 5 will be relieved of any strain that may be caused by the expansion of the fire-box sheet 3, as the said partition 5 is 65 free to participate in the expansion of the fire sheet 3 without interference from the connection of said partition with the outer sheet 4 by the bolts 7. In view of the fact that the partition 5 does not reach the bottom 70 of the boiler, a rapid circulation of water will be established between the sheets 3 and 4 of the boiler, and, consequently, the said partition does not only form of the screws 6 and the bolts 7 flexible stay bolts 75 but it prevents the formation of dead pockets of water in the boiler.

From the foregoing description, taken in connection with the accompanying drawings, the advantage of the construction and 80 operation of the device shown will be readily understood by those skilled in the art to which the invention pertains; and while I have described the principle of operation, together with the device which I now consider to be the best embodiment thereof, I 85 desire to have it understood that the device shown is merely illustrative and that such changes may be made as are within the scope of the appended claims.

Having thus described my invention, I claim as new and desire to secure by Letters Patent:

1. The combination with a pair of boiler sheets of a partition between said sheets, 95 screws connecting the partition to one of said sheets, and bolts connecting said partition to the other of said sheets.

2. The combination with a pair of boiler sheets of a partition suspended between the 100 said sheets, means connecting said partition to one of said sheets, and means connecting said partition to the other of said sheets, said second means leaving to said partition freedom of movement.

3. The combination with a pair of boiler sheets of a partition positioned between said sheets, screws threaded into said partition

and one of said sheets, said partition having apertures, bolts engaging said apertures and threaded into said second sheet of the boiler, said bolts having rounded heads in engagement with said partition, and means whereby said bolts can be manipulated.

In testimony whereof I have signed my name to this specification in the presence of two subscribing witnesses.

DENNIS J. O'BRIEN.
